UNITED STATES PATENT OFFICE

OLAF S. STROM, OF ALHAMBRA, CALIFORNIA, ASSIGNOR OF ONE-HALF TO SIMON A. ROSENFELD, OF LOS ANGELES, CALIFORNIA

LIGHTING FIXTURE

Application filed December 26, 1929. Serial No. 416,564.

My invention relates to lighting fixtures for ceilings and the like, and it has for a purpose the provision of a fixture including an electric lamp and a bowl housing the lamp, 5 the fixture being characterized by a simple and inexpensive means for suspending the two so that they are free to assume a vertical position and without the necessity of any adjustments of the parts thereof; suspension 10 means capable of being readily assembled and disassembled; and a bowl having a removable bottom through which access may be had to the lamp for substituting a new one when necessary, and without the requirement of removing the entire bowl, as is necessary in lighting fixtures as heretofore proposed.

It is also a purpose of my invention to provide a bowl having transparent portions 20 and translucent portions, and mirrored surfaces for reflecting the rays emanating from the lamp so that they are projected through the transparent portions to effect a very desirable form of indirect lighting.

25 I will describe only one form of lighting fixture embodying my invention and will then point out the novel features thereof in claims.

In the accompanying drawings.

Fig. 1 is a view showing in side elevation and partly in vertical section, one form of lighting fixture embodying my invention.

Figs. 2 and 3 are transverse sectional views taken on the lines 2—2 and 3—3, respectively, of Fig. 1, and looking in the direction of the arrows.

In carrying out my invention, I employ a conventional form of canopy 15 as a finish plate for an electrical conduit 16 which projects downwardly from a ceiling and through which extend the flexible conductors 17 for an electric lamp 18. The conductors 17 project a distance beyond the lower end of the conduit 16 so that the lamp 18 is free to assume vertical position. The lower end of the conduit 16 is screw threaded exteriorly as indicated at 19 to receive a ball 20 provided with a central opening 21 aligned with the bore of the conduit 16 in order that the conductors 17 may be extended through the ball, as illustrated in Fig. 1. A socket mem-

ber 22 loosely embraces the ball 20, and formed integral with this socket member are a plurality of radial arms 23 circumferentially spaced and provided with a slot 24.

When once associated with the conduit 16 the ball and socket member remains a fixed part of the conduit and constitutes the suspending member of a means for suspending a bowl for housing the lamp 18 to secure such projection of light rays emanating from the lamp as to produce indirect lighting.

The remainder of the suspension means comprises a suspended member including three hooks 25 and a flat ring 26 formed integral with the hooks and from which the latter rise. These hooks are circumferentially spaced to correspond to the spacing of the arms 23, and the bill of the hooks are adapted to seat within the slots 24 so that the member as a unit is suspended from the arms. A plurality of spring clips 27 are secured to and circumferentially spaced on the upper side of the ring 26, and these clips are constructed to receive and engage an annular bead 28 formed on a bowl designated generally at B, the clips and beads coacting to provide a detachable connection between the suspended member and the bowl.

The detailed construction of the bowl B will be described hereinafter, but suffice it to say for the present, that, the bowl is provided with a restricted opening at its upper end bounded by a collar 29, at the base of which, the bead 28 is formed. The bowl at its bottom is formed with a relatively large opening bounded by a collar 30, and through this opening access is had to the lamp 18 for applying or removing the latter and without the necessity of detaching the bowl from the suspension means. The bottom opening is normally closed by a closure 31 preferably formed of metal or any other suitable opaque or translucent material, and this closure is detachably secured to the bowl by means of spring clips 32 and 33. The clip 32 is secured at the inner side of the closure so as to have engagement with the inner face of the collar 30, the clip 33 being secured to the outer side of the closure and extended through a suitable slot of the closure 100

to engage the outer face of the collar. In this manner the two clips 32 and 33 coact to detachably secure the closure in spanning position with respect to the bottom opening of 5 the bowl. The removal of the closure from the bottom of the bowl may be readily effected by the provision of a handle 35 fixed to the closure centrally thereof, and so shaped as to provide an exterior ornament for the 10 closure.

In practice, the bowl B is applied to the suspension means by first associating the suspended member with the upper end of the bowl, the element being inserted into the 15 collar 29 through the bottom of the bowl and to a position in which the clips 27 engage the bead 28. It will be noted that once the ring 26 is applied, it forms a seat for the bead 28 and the adjacent portion of the 20 bowl, so that the suspended member cannot pass upwardly through the bowl. With the suspended member applied as described the hooks 25 are disposed upright within the collar 29 so that by passing the bowl upwardly 25 around the conductors 17 to a point in which the bills of the hooks 25 are disposed above the arms 23, the bowl may now be lowered to cause the bills to pass into the slots 24 thereby operatively connecting the suspended 30 member to the suspension member. Thus, the bowl is now suspended on the conduit, it being understood that in order to position the bills of the hooks with respect to the slots, it is necessary to slightly rotate the 35 bowl. With the bowl thus applied, it is suspended to swing about the ball 20 by the socket 22, and in consequence of which, the bowl is free to assume a true vertical position even though the conduit 16 may not be true 40 vertically.

In applying the bowl as above described, the closure 31 is of course removed, but following suspension of the bowl from the conduit, the closure is reapplied.

45 The bowl B is constructed of glass or similar material, and in addition to the collars 29 and 30, it is formed with body portions 36 and 37 of frusto-conical form, the lower body portion being larger than the upper, as will be clear from a consideration of Fig. 1. Both of these body portions are shaped circumferentially to provide a plurality of facets and these facets are frosted in order to render them translucent. The 50 horizontal parts 36^a and 37^a, respectively, are clear or transparent glass, while the interior surfaces of the facets of the lower portion 37 are mirrored, as indicated at 37^b, in order to provide reflecting 55 panels. The angularity of these panels with respect to the lamp 18 and the clear glass portions 37^a is such that, the rays from the lamp will be refracted and projected vertically through the clear glass portions. As these portions are horizontally 60

disposed, the light rays will be projected upwardly against the ceiling, and thus produce what is known in the art as indirect lighting. With respect to the bowl portion 37, those rays from the lamp 18 projecting upwardly will pass through the clear glass and thus outwardly against the ceiling. The frosted parts will be illuminated by the lamp to produce a dull illumination exteriorly of the bowl, which is desirable in fixtures of this 75 kind.

70 Although I have herein shown and described only one form of lighting fixture embodying my invention, it is to be understood that various changes and modifications may be made herein without departing from the spirit of the invention and the spirit and scope of the appended claims.

75 I claim:

1. A ceiling lighting fixture, comprising a conduit adapted to be secured to a ceiling so as to be pendant thereto, a ball on the lower end of the conduit, a socket embracing the ball, slotted arms carried by the socket, a ring, hooks carried by the ring and engaging within the slots of said arms for supporting the ring on the socket, and a bowl supported on the ring.

80 2. A ceiling lighting fixture, comprising a conduit adapted to be secured to a ceiling so as to be pendant thereto, a ball on the lower end of the conduit, a socket embracing the ball, slotted arms carried by the socket, a ring, hooks carried by the ring and engaging within the slots of said arms for supporting the ring on the socket, spring clips on the ring, a bowl having a shoulder engaged by the ring so that the bowl is supported on the ring, and a bead in the bowl 85 engaged by the clips to detachably secure the ring to the bowl.

85 3. A lighting fixture as embodied in claim 1 wherein conductors extend through the conduit, said ball being formed with an opening 90 through which the conductors extend so as to be pendant to the conduit, and a lamp carried by the conductors so as to be disposed within said bowl.

95 4. A lighting fixture as embodied in claim 1 wherein conductors extend through the conduit, said ball being formed with an opening 100 through which the conductors extend so as to be pendant to the conduit, said bowl having an open bottom through which access is had to the lamp, and a removable closure for said bottom.

105 5. A ceiling lighting fixture, comprising a conduit, a ball on the conduit, a socket embracing the ball, arms carried by the socket, a ring, hooks carried by the ring and engaging said arms for supporting the ring on the socket, and a bowl having a shoulder engaged by the ring so that the bowl is supported on the ring.

6. A lighting fixture as embodied in claim
5 wherein conductors extend through the con-
duit, said ball being formed with an opening
through which the conductors extend so as to
be pendant to the conduit, and a lamp car-
ried by the conductors so as to be disposed
within said bowl.
